(57) **CLAIM**

The ornamental design for a speaker, as shown and described.

DESCRIPTION

FIG. 1 is a front, right side, perspective view of a speaker showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an exploded front, right side perspective view thereof;

FIG. 9 is a front, right side perspective view thereof, shown in first environmental use, shown in reduced scale;

FIG. 10 is a top, right side perspective view thereof, shown in second environmental use, shown in reduced scale; and, FIG. 11 is a front, right side perspective view thereof, shown in third environmental use.

The broken lines in the figures illustrate the portions of the speaker and form no part of the claimed design.

The broken lines showing of audio player, sound bar, and stereo speaker in FIGS. 9-11 are for the purpose of illustrating environmental subject matter that forms no part of the claimed design.
